[57] CLAIM

The ornamental design for a headset, as shown and described.

DESCRIPTION

FIG. 1 is a perspective view of the preferred embodiment of the headset with the microphone in the down position;

FIG. 2 is a side view of the preferred embodiment of the headset with the microphone boom in the down position;

FIG. 3 is a side view of the preferred embodiment of the headset showing the earphone to which the microphone boom is not attached;

FIG. 4 is a front view of the preferred embodiment of the headset with the microphone boom in the full up position;

FIG. 5 is a top view of the preferred embodiment of the headset;

FIG. 6 is a bottom view of the preferred embodiment of the headset; and,

FIG. 7 is a perspective view of a first alternate embodiment of a monaural headset with the right earphone replaced by a rubber end cap and the left earphone with the attached microphone boom and the microphone boom in a partially down position.

FIG. 5

FIG. 4

FIG. 6

FIG. 2
